Phineas Bennett - Ithaca, N. Y.

(Patented Oct. 2, 1834. Registered Sept. 25, 1836.)

Letter's Patent.

The Schedule referred to in this Letter's Patent and making part of this
paper containing a description in the words of the said Phineas Bennett him-
self of his improvement in the Saw Saw-Mill Dog for which Letters Patent were
granted, dated the 2^d day of December 1834, which Letter's Patent are hereby cancelled

249.

in account of a defective specification.

So all whom it may concern—

Be it known that I, Phineas Bunting of the Town of Union in the County of Tompkins and State of New York have made a new and useful improvement in Sawmill Dogs, which I denominate the Sawmill Dog; and that the following is a full and exact description thereof as amended by me, the description, a specification in which a patent was granted to me therefor dated December 2^d. 1834, having been found defective; and which patent I am, therefore, about to surrender to the United States to be cancelled and re-issued; in accordance with the laws of that country and provided on the accompanying drawing A. 1. is a pack which is best made of cast iron. For ordinary purposes it may be made a half foot long, four inches wide and one inch thick. This and all other parts described whenever they are represented in the drawings either alone or in combination and designated by the same figures, or letters, this pack is to be elongated, grooved or notched, at each edge, so that it may be made to slide readily in the head and tail blocks of the carriage, to receive proper checks or guides, its plain side being upwards and on a level with the upper surfaces of the blocks, which blocks with their apertures are shown at A. 2. A ratchet wheel and a pinion which are used to give motion to the pack, also shown separately both being attached to the same shaft, and numbered 3 & 4. The ratchet wheel (3) is seen upright in the top perspective view of the head and tail blocks, but the pinion, being under the pack is not seen; it is to be understood that the uppermost of these figures represents the tail block and the lowermost, the head block. When the log is to be set, the ratchet wheel is to be turned by means of the lever A. 5. This lever works slowly on a pivot on the outer end of the shaft of the ratchet wheel and pinion and it has on it a pull, shown separately at A. 6. which pull is fastened to the teeth of the ratchet wheel and may be made to turn it in either direction, but is capable of being reversed, if a firm hold by the pull is thought necessary, there may be a double row of teeth like a saw tooth on the ratchet wheel, the double pull or separate pull, being adapted to them. The lever may be secured by hand, or by fastening it with a collar fastened on the head or tail block, as will be presently described. The log is to be held by means of dogs, made and having teeth formed with a ratchet, as shown at A. 7. These dogs work on hinge joints or eyes at their lower

2214. 8514 X

and, the lower part of the joint being firmly attached to the back, or upper side of the snake.

(This apparatus, sprung by pendulum self setting if desired and the machinery for this purpose may be arranged in various ways, one of the most convenient of which ways I have represented in the drawing. There is on the tail block an elbow at 7, connected by means of joints and a door lever with the ratchet wheel, as is distinctly shewn in the drawing both are connected together, and also in separate parts the outer end of the elbow at 7, which the saw mill carriage runs back being made to strike a stationary pin, the log will be set and the extent of the setting may be easily regulated, as will be evident to any competent workman, on the head block at 8 is an upright shaft capable of sliding up and down, the lower end of this is attached to the elbow joint as seen at 8 of the top of the upright shaft at 8, if struck by machinery attached to the saw gate at the instant the saw mill is set in motion after the carriage is run back, will effect the setting by the aid of the joints leading to the ratchet wheel, the machinery attached to the saw gate is used by me in a small wood, an lever fastened to one end to a stationary post and at the other to the saw gate, leaving a piece of wood projecting therefrom, so as to strike the before mentioned upright shaft. The lever at 10, attached to the head block, may by the action of an inclined plane affixed to the floor, and acting on the outer end B, and leaving on its inner end D, a hook C, draw the setting apparatus back nearly to be again closed up as before.

What I claim is, my invention is the arrangement for self setting as herein described, not intending however by this claim to limit myself to the precise manner of arranging the parts as herein set forth, but to any the same as I may think proper, whilst I proceed substantially upon the principles herein fully made known.
